UNITED STATES PATENT OFFICE

RAY F. GOOD, OF LYKENS, PENNSYLVANIA

METALLIC SHOE LACE TIP

Application filed March 4, 1930. Serial No. 433,127.

This invention relates to an improved permanent metallic tip for shoe laces and the like.

Heretofore it has been found that the tips of shoe laces, which are either of wire which is wrapped about the end portion of the lace, or are of resilient sheet metal bent to engage the lace, soon become lost or mutilated so that much difficulty is experienced in passing 10 the end portion of the lace through the eyelet of a shoe or the like.

One object of the invention is, therefore, to provide a lace tip which will not become separated from the lace and which cannot be 15 easily mutilated.

Another object of the invention is to provide a device of this character employing wires of various lengths which are bent to form a substantially conical tip, which wires 20 are surrounded by a protecting cover.

A further object of the invention is to provide a lace tip which will be a sealed unit when in operative position.

Still further objects of the invention not 25 specifically mentioned in the foregoing, will appear during the course of the following description.

In the drawings:

Figure 1 is a side elevation of the tip in 30 position upon a lace.

Figure 2 is a perspective view showing the wires extending through the lace and before being bent.

Figure 3 is a perspective view showing the 35 wires bent and twisted to form a conical skeleton.

Figure 4 is an enlarged side elevation showing the protecting cover before being bent to shape.

Figure 5 is an enlarged longitudinal sectional view of the complete tip.

Figure 6 is an enlarged vertical sectional view on the line 6—6 of Figure 5.

Referring more particularly to the drawings, the numeral 1 indicates a portion of a conventional lace such as is employed in connection with shoes, corsets, and the like. The edges of the lace are turned inwardly upon themselves and meet to form a substantially 50 conical end portion 2.

Extending through the conical end portion of the lace and disposed at angular relations to each other are resilient wires 3, 4 and 5 which are of different lengths, the wire 3 being slightly longer than the wire 4 and said wire 4 being slightly longer than the wire 5. As clearly illustrated in Figure 3 of the drawings, the wires are bent forwardly past the end portion 2 of the lace and the free ends of such wires are twisted together, or, if desired, 55 the ends of the wires may simply overlie each other and need not be twisted together. As the wires are of different lengths, a substantially conical skeleton will be formed, and, furthermore, as said wires are in engagement 60 with the lace, it will be impossible for the skeleton to become detached from said lace as long as such lace is intact.

Surrounding the skeleton and the end portion 2 of the lace is a resilient sheet metal protecting cover 6 which is bent and pressed into conical shape with a relatively small opening 70 formed in the outer end.

The wires 3, 4 and 5, as well as the cover 6, 75 are preferably coated so that solder will adhere more effectually thereto and after the cover is applied the device is dipped in solder, which is preferably of a relatively low melting point so that burning of the lace will be prevented.

The solder is permitted to circulate 80 about the skeleton between the strands of the skeleton as well as between said skeleton and the cover and also to adhere to the fabric of the lace, thereby effectually anchoring those parts in assembled unitary relation, while any 85 looseness between the parts will be prevented, and the tip formed into a solid unitary structure.

Furthermore, the solder will form a coating externally of the cover permanently 90 uniting the longitudinal edges of the cover at the seam therein. Thus it can be readily seen that a lace tip has been provided which will be permanent.

What is claimed is:

1. A device of the class described including, 95 in combination with a lace, a skeleton anchored thereto, said skeleton comprising a plurality of strands, and a cover for said skeleton.

2. A device of the class described including, 100

in combination with a lace, a skeleton anchored to said lace, a cover for said skeleton, and means uniting said skeleton and cover as a unit.

5 3. A device of the class described including, in combination with a lace, a wire extending through the lace and bent to form a skeleton, protecting means embracing the skeleton, and means uniting the skeleton and protecting
10 means as a unit.

4. A device of the class described including, in combination with a lace, a wire extending through the end portion of said lace and bent to form a skeleton, a protecting cover surrounding the skeleton and the end portion of
15 the lace, and means uniting said skeleton with said cover and filling the cover.

5. A lace tip including, in combination with the end portion of a lace, a plurality of wires
20 of different lengths extending through said end portion of the lace and bent to provide a forwardly disposed conical skeleton, protecting means for the skeleton, and means uniting the skeleton with said protecting
25 means as a unit.

6. A lace tip including, in combination with a lace, a conical skeleton engaging the lace, a conical protecting cover for said skeleton, and means anchoring the skeleton and cover
30 as a unit.

In testimony whereof I affix my signature.
